AIR DEHUMIDIFIER UNIT

William R. Steiner, Detroit, Mich., assignor to General Motors Corporation, Detroit, Mich., a corporation of Delaware

Application May 1, 1956, Serial No. 41,295

Term of patent 7 years

(Cl. D62—4)

Fig.1.

Fig.2.

Fig. 3.

Fig. 4.

Fig. 5.

Fig. 6

Figure 1 is a perspective view showing the front, top and one side of an air dehumidifier unit embodying my new design;

Figure 2 is a perspective view showing the rear, top and other side of the unit;

Figure 3 is a side view of the unit;

Figure 4 is a front view thereof;

Figure 5 is a section taken on line 5—5 of Figure 3; and

Figure 6 is a section taken on line 6—6 of Figure 4. I claim:

The ornamental design for an air dehumidifier unit, as shown.
